DOOR FOR AUTOMOBILES

Willard L. Morrison, Chicago, Ill.

Application June 30, 1933, Serial No. 678,399

6 Claims. (Cl. 296—44)

This invention relates to doors for automobiles and process of making same and has for its object to provide a new and improved device and process of this description. The invention has as a further object to provide a door for automobiles which shall have a space below the window arranged so that an arm rest may be easily and quickly attached thereto after the door has been manufactured, so that the automobile can be sold without the extra charge of the arm rest, but anyone who wants an arm rest afterwards can buy it and put it on. The invention has as a further object to provide a cheap and effective process for manufacturing automobile doors. The invention has other objects which are more particularly pointed out in the accompanying description.

Referring now to the drawings, Fig. 1 is a view of one form of automobile having doors embodying the invention;

Fig. 2 is an inside view of the front door illustrated in Fig. 1;

Fig. 3 is a sectional view taken on line 3—3 of Fig. 2;

Fig. 4 is a sectional view taken on line 4—4 of Fig. 2;

Fig. 5 is an enlarged sectional view similar to Fig. 3 with parts broken away;

Fig. 6 is an enlarged view of the portion of the door where the arm rest is attached;

Fig. 7 is an enlarged sectional view taken on line 7—7 of Fig. 6;

Fig. 8 is a sectional view taken on line 8—8 of Fig. 7;

Fig. 9 is a perspective view of the arm rest separated from the door;

Fig. 10 is an enlarged view showing a portion of the inside of the door where one arm of the arm rest is to be attached;

Fig. 11 is a sectional view taken on line 11—11 of Fig. 10;

Fig. 12 is a sectional view taken on line 12—12 of Fig. 2 with parts broken away;

Fig. 13 is a sectional view taken on line 13—13 of Fig. 2;

Fig. 14 is a sectional view taken on line 14—14 of Fig. 2;

Fig. 15 is a view of the upper part of Fig. 12 before the connecting flanges are bent to overlap;

Fig. 16 is similar to Fig. 13 before the connecting flanges are bent to overlap;

Fig. 17 is a perspective view showing the two metal sections of the door and the intermediate

non-metallic section in position to be attached together.

Like numerals refer to like parts throughout the several figures.

Referring now to the drawings, I have shown an automobile I provided with a door embodying this invention. In this construction the automobile is provided with the front doors 2 and the rear doors 3. The front doors are provided with the front pivoted deflector section 4 and the rear pivoted deflector section 5. The front deflector section is pivoted at 6 and 7 in the window opening, and the rear deflector section is pivoted at 8 and 9. The door below the window is hollowed out so as to form the space 10. The door is formed out of two stamped metal sections, the outside section 11 and the inside section 12. The outside section is cut away at the top to form the window opening 13 and the metal around the window opening is forced inwardly to form the ledge 14. The section 12 is also cut away to form the window opening 13 and the metal is bent to form the outwardly projecting ledge 15 for the upper part of the window opening. The portion of the inner section 12 below the window opening is bent inwardly to the position shown in Figs. 3 and 5, and just below the window it has the outwardly bent portion 16, see Fig. 12. At the sides the inner section 12 has the inwardly bent flanges 17 and 18 and at the bottom the inwardly bent flange 19, so as to form the outer frame of the door. The two sections when formed are pressed together, there being between them a section 20 of non-metallic material, see Fig. 17. When the two sections 11 and 12 are pressed together the parts above and below the window opening are as illustrated in Fig. 15. The upper edge 21 of the section 11 is bent around the upstanding edge 22 of the ledge 15 of the section 12, as shown in Fig. 12. The projecting portion 23 of the ledge 15, shown unbent in Fig. 15, is bent around over the portion 24 of the ledge 14 of the section 11, as shown in Fig. 12.

Below the window opening the outer section 11 has the inwardly bent portion 25 with the upstanding portion 26, and the portion 16 of the section 12 has the upstanding portion 27, and this upstanding portion 27 is brought to the position shown in the lower part of Fig. 15. This upstanding part 27 is then bent around the upstanding part 26, as shown in the middle portion of Fig. 12.

Referring to the rear portion of the window opening, sections of which are shown in Figs. 13

and 16, the outer section 11 is bent inwardly at 28 and has the angular portion 29. The inner section 12 has the projecting edges 30 and 31, while the outer portion has a projecting edge 5 32. When the parts are brought together they are in the position shown in Fig. 16. The part 30 is then bent over the part 29 and the part 32 over the part 31, as shown in Fig. 13. At the rear edge of the door below the window opening 10 the inner section 12 has the outwardly V-shaped portion forming the flange 17 with the laterally bent portion 34, and the outer section 11 has the projection 35 which is bent over the flange 34, as shown in Fig. 14. At the bottom the 15 inner section 11 is bent to form the flange 19. This flange has a laterally bent portion 36, see the bottom of Fig. 12, and the outer section 11 has the portion 37 which is bent therearound.

It will be seen that this forms a strong durable 20 door with the proper outstanding flanges 17, 18 and 19 about it. It will further be seen that this door is made out of two stamped pieces with the edges properly bent and clamped together to form a secure, strong and durable structure.

25 The inner section 12 may be arranged so that an arm rest can be easily attached thereto. When the door is made up and the automobile assembled the inner section 12 is covered with cloth or suitable upholstery. This inner section 30 12 is provided at suitable distances apart with the openings 38, see Figs. 6 to 10. These openings have contracted portions at their lower ends, as shown at 39. The openings are normally covered by the cloth or upholstering material 40, see Fig. 11. The arm rest 41 is provided with the fastening devices 42 which have enlarged heads and a contracted neck 43. Back of these openings the non-metallic section 20 is 35 cut away to form the openings 44, see Fig. 7. When it is desired to attach the arm rest 41, it is 40 only necessary to locate these holes with the fingers and then either cut away the upholstering material 40 at these points, or simply place the fastening devices 42 into the upper enlarged 45 ends 38 of the openings and then move the arm rest downwardly until the contracted necks 43 enter the contracted portions 39 of the openings, as shown in Fig. 8. It will therefore be seen that the arm rest can be easily and quickly inserted 50 in position as an accessory after the automobile is manufactured, and this may be either at the time of sale or at any other later time.

It will be seen that I have here a door made up of two metallic sections with the edges of the 55 sections bent to form the frame of the door, the two sections being connected together by bending the metal of one section around portions of the other sections.

It will further be seen that in this door the 60 metal of the two sections forms the window reveal.

It will further be seen that I have here a door with a wall having concealed means for attaching an arm rest thereto.

65 I have described in detail a particular construction, but it is of course evident that the parts may be varied in many particulars without departing from the spirit of the invention as embodied in the claims hereto appended, and I therefore do not limit myself to the particular 70 construction shown.

I claim:

1. A door for automobiles comprising an outer wall, a window in said wall, said outer wall made of two sections, each having a window opening therein, the part of the inner section below the 5 window being outside of the vertical plane through the window, a part of said section at the window being bent inwardly and extending across under the window to the other side thereof, the sections being placed together and attached one to the other to form the door structure.

2. A door for automobiles comprising an outer wall, a window in said wall, said outer wall made of two metallic sections, each having a window 15 opening therein, the part of the inner section below the window being outside of the vertical plane through the window, a part of said section at the window being bent inwardly and extending across under the window to the other 20 side thereof, the metallic sections being placed together and attached one to the other to form the door structure, and a non-metallic section between said metallic sections.

3. A door for automobiles comprising an outer 25 wall, a window in said wall, said outer wall made of two metallic sections, each having a window opening therein, the part of the inner section below the window being outside of the vertical plane through the window, a part of said section 30 at the window being bent inwardly and extending across under the window to the other side thereof, the edges of one of said metallic sections being bent laterally to form the door frame, the two sections being connected together.

4. A door for automobiles comprising an outer wall, a window in said wall, said outer wall made of two metallic sections, each having a window opening therein, the part of the inner section below the window being outside of the vertical 40 plane through the window, a part of said section at the window being bent inwardly and extending across under the window to the other side thereof, the edges of one of said metallic sections being bent laterally to form the door frame, the 45 edges of one section being bent around portions of the other section to fasten the two sections together.

5. A door for automobiles comprising an outer wall, a window in said wall, said outer wall made 50 of two metallic sections, each having a window opening therein, the part of the inner section below the window being outside of the vertical plane through the window, a part of said section at the window being bent inwardly and extending 55 across under the window to the other side thereof, the edges of one of said metallic sections being bent laterally to form the door frame, the metal of the sections being bent laterally around the window opening to form the 60 window frame, the edges of one section being bent around portions of the other section to fasten the two sections together.

6. A door for automobiles having a window 65 therein, comprising two metallic sections formed into shape, each having a window opening therein, the metal of the sections around said window opening extending entirely across the window opening, a portion thereof being in the plane of the window.

WILLARD L. MORRISON.
